UNITED STATES PATENT OFFICE.

PHILIP A. FUCHS, OF MILWAUKEE, WISCONSIN, ASSIGNOR TO TURBINE SEWER MACHINE COMPANY, OF MILWAUKEE, WISCONSIN.

SEWER CLEANER.

Application filed April 21, 1926. Serial No. 103,453.

This invention relates to improvements in sewer cleaners of the general type disclosed in Letters Patent of the United States, numbered 1,163,624 and granted to W. J. Stevenson, P. A. Fuchs and W. Hiecke, Jr., December 7, 1915. In such cleaners, a water driven turbine is employed to drive a rotary head provided with a set of blades for cutting accumulated material from the walls of the sewer, the power water being also utilized to carry away the débris.

The object of this invention is to provide means for more effectively utilizing the force of the power water to clean the blades and carry away the débris after the water has been delivered from the rotor of the turbine.

Also, to provide an improved thrust bearing which will be less exposed to the action of sand or grit than the thrust bearing disclosed in said former patent.

In said former patent, the water was delivered from the rotor of the turbine against a bell shaped neck piece of the rotary blade carrying head, said neck piece serving as a spreader to direct the water outwardly in the direction of the blades and against the interior surface of the water in the sewer. By this invention, a neck piece or spreader of the general contour disclosed in said former patent is provided with a series of helical channels which form continuations of the bucket grooves of the rotor, whereby the water may be delivered to the blades and the sewer walls in the form of concentrated jets which are found to be much more effective for cleaning the blades and carrying away material than the conical sheet or spray delivered by the spreader disclosed in said former patent.

In the drawings:

Figure 1 is a side elevation of the improved sewer cleaner, with the supporting runners omitted.

Figure 2 is an enlarged detail view, partly in longitudinal section, showing the relatively stationary and rotary grooved members of the turbine in assembled relation to the head.

Like parts are identified by the same reference characters throughout the several views.

The cylinder 1 is provided with a hose coupling 2 at its rear end and its forward end is provided with a member 4, the inte-

rior surface of which is flared or conically enlarged as shown at 5. A water actuated motor is mounted in the cylinder 1 near the flared end thereof and this includes a stationary member 6 which may be secured to the wall of the cylinder but which is provided with helical water directing grooves 7. A shaft 10 extends through the member 6, or is formed integrally therewith, and an impact motor or turbine rotor is mounted on this shaft with anti-friction thrust bearings 12 between it and a collar 13 fixed to the shaft 10 and held in position by a nut 14 screwed upon a threaded portion of said shaft 10. Similar thrust bearings 12^a are interposed between the rotor and the relatively stationary member 6. The front end of the shaft 10 is provided with an eye piece 15 to facilitate the attachment of a cable whereby the device may be drawn through a sewer. This eye piece is preferably screwed upon the shaft 10 and secured thereto by a cotter pin 15^a.

The rotor comprises a bucket grooved member 16 and a head 17 connected to the member 16 by a neck piece 18 having a generally conical or bell shaped form, enlarged in the direction of the head. The member 16 is provided with a series of helical grooves 19 curving in the opposite direction from that of the grooves 7 and these grooves 19 extend into the neck piece beyond the flaring portion or end piece 4 of the casing as shown at 19^a. The portions 19^a of the groove constitute continuations of the buckets 19 and they are progressively shallower as they approach the headpiece, whereby the water following these grooves is delivered outwardly in the direction of the blades 20 and their shanks 21 which are secured to the headpiece 17. The blades operate to cut material from the sewer wall, as described in said former patent. The extension of the grooves 19^a along the neck piece tends to confine the water to the grooves while it is being deflected outwardly and therefore the water is delivered to the blades in the form of separate jets, one for each groove. This avoids dissipating the force of the stream, or streams, by reason of air resistance and the spreading of the water into a conical sheet, as is the case in the structure disclosed in said former patent. These forcible jets of water are much more effective to carry away the fragments of material instead of

massing or concentrating them. The material contains large quantities of grease and a sheet of water delivered against the fragments tends to mass them instead of splitting them up into smaller fragments, as is the case where they are struck by jets as above described.

In said former structure, the forward thrust bearings 12 were exposed to sand and grit. In the improved construction the shaft collar 13 is provided with a cylindrical portion 13^a which encircles the bearings and is preferably provided with an in-turned flange 13^b which extends into close proximity with the hub 25 upon the end of which the cone 26 is formed, thereby retaining the bearing balls 27.

In all other particulars the structure of the improved sewer cleaner may be assumed to correspond with that disclosed in said former patent and further description thereof is deemed unnecessary.

I claim:—

1. In a sewer cleaner, the combination with a rotary blade carrying head, of a driving turbine having curved bucket cavities, and a spreader connecting the turbine with the head and having grooves which are continuations of the bucket cavities along an outwardly curving surface, said spreader grooves being adapted to direct the power water in the direction of the blades carried by the head.
2. In a sewer cleaner, the combination with a head having radial blades, of a water motor operatively connected to drive the

head, and a grooved spreader interposed between the turbine and the head and provided with grooves having progressively outwardly curving walls, adapted to direct jets of power water from the turbine toward the blades.

3. In a sewer cleaner, the combination with a head having radial blades, of a water motor operatively connected to drive the head, and a grooved spreader interposed between the turbine and the head and provided with grooves having progressively outwardly curving walls, adapted to direct jets of power water from the turbine toward the blades, said spreader grooves decreasing in depth in the direction of the head.

4. In a device of the character described, the combination with a shaft and a head rotatably connected therewith, a water motor mounted on said shaft and operatively arranged to drive said head and to deliver its output in the direction of said head, said head including a tapered portion in the path of delivery of water from said motor, and provided with grooves extending in the direction of its outer periphery, whereby to discharge such water from individual grooves in the form of jets.

5. In a turbine sewer cleaner, a rotor including a bucket grooved turbine at one end, an exposed head at the other end provided with cutting blades, and an intermediate portion provided with jet directing helical channels, the bottom walls of which also curve outwardly from the axis of the rotor.

PHILIP A. FUCHS.
